UNITED STATES PATENT OFFICE.

SAMUEL TYLER, OF WHEELING, WEST VIRGINIA, ASSIGNOR TO WARWOOD TOOL COMPANY, OF WHEELING, WEST VIRGINIA, A CORPORATION OF WEST VIRGINIA.

BIT CONNECTION FOR MINERS' AUGERS.

No. 909,968.

Specification of Letters Patent.

Patented Jan. 19, 1909.

Application filed February 4, 1908. Serial No. 414,191.

To all whom it may concern:

Be it known that I, SAMUEL TYLER, a citizen of the United States of America, and resident of Wheeling, county of Ohio, and State of West Virginia, have invented certain new and useful Improvements in Bit Connections for Miners' Augers, of which the following is a specification.

This invention relates to improvements in miners' augers, and more particularly to a bit-connection for such augers; and it consists in the particular construction, arrangement and combination of parts which will hereinafter be fully described.

Hitherto, a rod-like stem or shank has in all cases been welded to the butt-end of the bit, and the end of this shank and the adjacent end of the brace have been provided with screw-threads and coupled together by means of a socket-coupling having interior screw-threads in its opposite ends. The welding of the stem or shank to the bit not only requires skilful work in order to prevent breaking at this point, but it is also a tedious and expensive operation.

The purpose or object of the present invention is to provide a device whereby bits may be readily connected directly to the brace-rods without the necessity for the provision of such rod-like shanks, thereby dispensing with the abovementioned welding.

In describing the invention in detail, reference is herein had to the accompanying drawing, forming a part of this specification, in which—

Figure 1 is a side elevation of a miner's auger showing my invention applied thereto; Fig. 2 is an enlarged top plan view of the invention, illustrating the application thereof; Fig. 3 is a longitudinal section on the line 3—3, Fig. 2; Fig. 4 is a cross section on the line 4—4, Fig. 2; and Fig. 5 is a side elevation of the coupling member.

Referring to said drawing, in which like reference characters designate like parts throughout the several views—1 indicates the horizontal arm of an ordinary form of miner's brace 2, said arm having a threaded end 3, and 4 indicates the bit which I employ in connection with such brace, said bit having a short longitudinal extension 5 of the helically-twisted or coiled portion, said extension being preferably of double convex form in cross section.

For connecting the threaded end 3 of the brace-arm 2 and the extension 5 of the bit, I provide a coupling member 6 having in one end an interiorly-threaded socket 7 in which said threaded end is received and having in its opposite end a double concave socket 8 in which said extension is received. The said extension fits neatly in the socket 8, and, owing to the relative formations of said extension and the socket, lateral movement of the former with relation to said coupling member is prevented. One or more screws or rivets 9 projected through registering holes in the coupling member and in the bit-extension serve to rigidly hold said bit in place. Side-slots 10 opening into said socket 8 through the opposite sides or edges of the coupling member admit of the projection therethrough of the lateral edges of said extension and, at the same time, admit of the jaws 6^a being slightly sprung inward to effect the clamping of said extension 5.

It will be noted that the usual form of bar of which the bit is formed is that of the extension 5 hereinbefore described; hence no special shaping of said extension is required, it being only necessary to insert the end of the extension within the socket 8 of the coupling member 6.

Having thus described my invention, what I claim as new, and desire to secure by Letters Patent, is—

1. In a miner's auger, a coupling connecting the brace-arm and the bit, said coupling being of less width than the diameter of said bit and consisting of a member having said brace-arm rigidly mounted in one end thereof, a double concave socket in the opposite end of said member, said socket having an extension formed on said bit mounted therein and projecting laterally through side-slots in said member, said extension being untwisted and of uniform size and shape with the blade of which the bit is formed, and rivets for securing said bit end in fixed position in said socket.

2. In a miner's auger, a brace having an arm with a threaded end, a twist-bit having an untwisted extension, said extension being double convex in cross section and of uniform size and shape with the blade of which the bit is formed, a coupling connecting said arm and said extension, said coupling being of less width than said extension so as to

admit of its entering bores formed by said bit, and consisting of a member having a threaded socket in one end in which said threaded end is held and a socket in its opposite end in which said extension is mounted, the last mentioned socket opening through opposite sides of said member to allow the edges of said extension to project outward therethrough and whereby a pair

of jaws are formed for clamping engagement with said extension.

In testimony whereof I affix my signature in presence of two subscribing witnesses.

SAMUEL TYLER.
